Primary Examiner — Messina L Smith*Assistant Examiner* — Jillian Mazzola(57) **CLAIM**

The ornamental design for an LED backpack, as shown and described.

DESCRIPTION

FIG. 1 is a perspective view of an LED backpack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in FIGS. 1, 3, 4, and 5 represent stitching lines that form part of the claimed design. The broken lines in FIG. 7 depict portions of the LED backpack that form no part of the claimed design.

1 Claim, 7 Drawing Sheets(56)
